TELEMETERING TRANSMITTER FOR A PROJECTILE

Allen V. Astin, Bethesda, Md., assignor to the United States of America as represented by the Secretary of the Navy

Application October 7, 1944, Serial No. 557,712

2 Claims. (Cl. 340—208)

(Granted under Title 35, U. S. Code (1952), sec. 266)

This invention relates to a radio sonde for an airborne vehicle, and particularly to telemetering transmitters adapted to furnish at a remote point a continuous record, both qualitative and quantitative, of conditions prevailing at the point of transmission.

An object of the invention is to provide a radio transmitter so compact and rugged in its nature that it may be incorporated in a bomb or projectile and which functions while the bomb or projectile is in flight. It will readily be appreciated, however, that the apparatus of the invention is equally applicable to the automatic transmission of desired information under conditions less rigorous.

The embodiments of the invention herein disclosed are so arranged and constructed as to be adapted for installation in explosive ordnance equipped with proximity firing or fuzing means, and to function in such manner as continuously to transmit an indication of the functioning of, and the conditions prevailing in, such proximity firing or fuzing apparatus. The record thus automatically transmitted may be recorded on paper, film or in any other convenient manner to permit convenient study.

An important object of the invention is to provide an automatic radio transmitting and oscillation generating mechanism of extremely compact and rugged construction, the parts of which are so designed that steady, uniform and accurate comparative record transmission is provided throughout the flight of a bomb or projectile carrying the same.

Another object of the invention is to provide radio signal generating means so constructed that it automatically incorporates with the transmitted signal a comparison pulse or signal of known amplitude, by means of which the magnitude of significant currents existing in fuzing circuits or other apparatus to be checked may be gauged.

Another object is to provide a radio signal generator which is adapted to furnish a continuous indication of the operation of a photocell, or of electrical components of photo-electric proximity fuzes during flight of a projectile containing the same, whereby there may be obtained at a remote station a continuous record of the photocell currents prevailing throughout a desired time, as during the operation of the photo-electric fuzing means.

Another object of the present invention is to provide improved means whereby a battery or electrolytic cell may be accurately tested from a remote point.

Another object is to provide an improved device of the character indicated which eliminates the interfering effects of radiation reflected by objects passing or near the source of radiation.

An object related to that last stated is to provide apparatus of the indicated character employing frequency modulation, the arrangement being such that sources of reflective and other interference are prevented from hampering the effective operation of the apparatus.

Other objects and advantages will become apparent

2

upon consideration of the present disclosure in its entirety.

In the drawings:

Fig. 1 is a schematic diagram of a radio transmitting system employing amplitude modulation and constructed in accordance with the present invention;

Fig. 2 is a schematic diagram of a modified arrangement in which frequency modulation is employed, with means for adjusting the frequency by varying the grid biasing effect of the input signal;

Fig. 3 is a similar schematic diagram of another modified construction employing crystal control of the carrier frequency;

Fig. 4 is a schematic diagram of another modified arrangement adapted to report conditions prevailing in a circuit incorporating a photo-electric cell;

Fig. 5 is a partly diagrammatic view corresponding to a longitudinal diametric section of the nose portion of an aerial bomb provided with an inductance tuned antenna adapted to serve as the radiating system for a radio transmitter constructed in accordance with the present invention;

Fig. 6 is a similar view showing a capacity tuned antenna mounted upon the nose of a bomb;

Fig. 7 is a similar view of the nose portion of a rocket projectile provided with antenna means streamlined to coincide with the nose of the projectile;

Fig. 8 is a fragmentary perspective view of the tail portion of a bomb equipped with radio transmitting means constructed in accordance with the present invention, and provided with an antenna of another somewhat modified construction;

Figs. 9, 10, 11 and 12 are oscillograms of records transmitted by the improved radio transmitting mechanisms under varying conditions; and

Fig. 13 illustrates use of the embodiment of Fig. 2 for transmitting changes in potential.

The amplitude modulated circuit of Fig. 1 consists essentially of a standard signal generator, modulator and carrier oscillator portions, generally designated S, M and C, respectively. The output of the carrier oscillator feeds a dipole antenna system, consisting of the antenna proper and the bomb or rocket casing, the antenna system being coupled to the output of the carrier oscillator by means of inductance 22 and plate coil 21. The carrier frequency is adjustable by means of a variable condenser 23 which provides coupling between and is connected to the plate coil 21 and grid coil 24 of the carrier oscillator tube 25, the condenser being connected to each coil near the mid point thereof.

The output of the radio proximity fuze, or other device to be tested, is fed to the modulator M at point 26, and signals generated by the radio fuze system are thereby impressed upon the carrier output and radiated therewith by the dipole, in the manner clearly indicated in the diagram Fig. 1.

A standard or comparison signal is also radiated with the carrier, being generated by the signal generator S, which is arranged to operate as a blocking oscillator. The output of the blocking oscillator S is fed to the grid of modulator 27 in parallel with the output signal from the fuze. The amplitude of the pulse of the blocking oscillator can thus be used as a standard of comparison at the receiving station, permitting the output of the fuze to be compared with it to furnish an indication of the amplitude of the fuze output.

The periodic blocking action results from the arrangement of resistance 44 and capacitance 45 in parallel in the grid circuit of tube 46. The grid and plate coils 47, 48 of signal generator tube 46 are inductively coupled, as indicated in dotted lines. When the tube 46 is in the oscillating condition, its grid swings positive in each half

cycle, and during each such half cycle it accumulates electrons from the grid circuit, which includes the filament 49, resistance 44 and condenser 45. The rate of accumulation of electrons, which tend to bias the grid negatively, depends upon the amplitude of oscillation and the value of condenser 45. The value of resistance 44 does not appreciably affect this rate since, in the oscillating condition, the grid-filament resistance is relatively low. As the grid accumulates electrons it becomes progressively more negative with respect to filament 49 until the negative bias is sufficient to block the tube from oscillating. At this instant an excess of electrons is accumulated on the grid and connected plate of condenser 45. When oscillation has ceased there is no longer a positive driving potential in grid coil 47, so that the accumulated electrons on the grid and connected condenser plate leak off to ground through resistance 44. When sufficient electrons have left the grid to raise its potential to within the oscillating range, the tube will again break into oscillation and the cycle will be repeated.

It will be apparent that the pulsing period of the signal generator can be adjusted by changing the value of resistance 44 or condenser 45, since the former affects the rate of leakage of electrons to ground, and the latter determines in part the rate of accumulation of electrons by the grid, the grid-filament potential difference being established largely through condenser 45, for high frequencies.

While suitable values for the various circuit components of Fig. 1 have been shown, it will be understood that these may be varied as conditions may dictate. The values of the plate and grid circuit components of the transmitter tube 25 are adjusted to give maximum ratio of amplitude to frequency modulation and also to provide as wide as possible a range of linear modulation, since the presence of frequency modulation in an audio modulation system is undesirable when quantitative measurements are desired.

The presence of appreciable frequency modulation evidences itself by a tendency of the phase of the audio output of the receiver to reverse at some point in the tuning range. At the point of reversal, the effective modulation will be zero or approximately zero, and this minimum audio output is frequently near the maximum carrier indication so that it is then impossible to use the carrier indicator on the receiver as a tuning indicator, and tuning must be done by adjusting for maximum amplitude of the standard signal as viewed in the oscilloscope.

The frequency of the standard signal generator pulse may be approximately five cycles per second. It will be apparent that the amplitude is calibrated in terms of a signal applied at the input 26 of modulator tube 27, the other input terminal being of course ground 28. The standard signal may conveniently be made equivalent to about five volts, applied to the grid of tube 27, and the modulation is linear in response up to eight or ten volts applied to the grid of this tube. If it is desired to measure higher voltages, a potential divider can be introduced in the grid circuit to extend the range, although this would also increase the effective noise level.

Fig. 9 shows a laboratory test calibration of the apparatus of Fig. 1 as given by an oscillogram made during an actual test of the apparatus. The sharp regular pulses 29 are those resulting from the action of the signal generator S for comparative purposes, while the single larger pulse 30 represents an actual positive five volt pulse signal applied at input 26 of the modulator tube 27.

An oscillographic record of an actual drop test on a radio transmitting apparatus of this type mounted in and dropped with a bomb is shown in Fig. 10. In this case the comparison signals 31 are of the order of five volts positive applied to the grid of the modulator, while the background pulses 32 are due to microphonics present in the radio transmitter system. The background pulses

in this case amount to less than plus or minus three quarters of a volt. The record was made from the last portion of an eight thousand foot drop, in which case the microphonics are most severe. For this unit the modulation was linear up to eight volts, giving an eight to one range for dependable voltage measurement. The regularly spaced dots 33 were made by a neon light actuated by a 60-cycle current source to serve as a time scale on the oscillogram.

While the mechanical mounting and disposition of the circuit components is a matter of choice, the unit is preferably dipped in paraffin or other wax to prevent vibration of the circuit parts, although it may be sufficient to bind only the radio frequency components with the wax.

Certain limitations are involved in the use of high frequency amplitude modulation in radio transmitting apparatus of this class, due to interference between direct radiation from the apparatus and reflected radiation. When the mechanism is contained in a bomb, reflection from the bomber occurs, and persists to approximately 1000 feet below the bomber; even at this distance amounting to approximately 2 percent of the modulation. Reflection also occurs from the target or any other object which the apparatus may pass. The amplitude of the interference peaks decreases and their frequency increases with time, the peaks being one half wave length apart in the path of the falling bomb. The presence of this interference handicaps the use of this type of apparatus for any tests other than those in which the bomb or projectile is free in flight.

Considerable interference is encountered in the operation of apparatus constructed as above described, and it may for the indicated reasons be desirable to employ frequency modulation, which may be done by adjusting the constants of the transmitter components to give maximum frequency modulation. When frequency modulation is used interference signals due to reflections from the bomber and other objects are eliminated, the interference being primarily amplitude modulated. A frequency modulated radio transmitter may therefore be used for tests against targets. A further advantage is that tuning can be made on the carrier indicator. Although trouble from microphonics is somewhat more pronounced in the case of frequency modulation, this can be considerably reduced by shock-mounting the device.

Fig. 2 shows a frequency modulated arrangement in which the frequency of the audio oscillator A used as a standard or comparison signal generator can be varied by changing its grid bias or grid resistance. The fuze signals or other signals to be measured are applied directly to the grid of tube 34 at point 35 and at ground 36A. Tube 34 modulates the carrier developed by the oscillator tube 36. An audio signal is obtained whose frequency is a function of the grid bias.

Grid and plate coils 37, 38 of the carrier oscillator are inductively coupled, as indicated. A tuning condenser 39 is used, as in the embodiment previously described. The grid and plate coils 40, 41 of the signal generator A are also inductively coupled, and the dipole 42 is inductively coupled to the plate coil 38 of the carrier oscillator by means of coil 43.

Resistance 50 is connected in the grid circuit of tube 34 in parallel with condenser 51 so that the audio or modulating frequency of tube A can be adjusted by changing the value of resistance 50 or capacitance 51. The signals applied to the grid circuit at point 35 will therefore alter the grid bias to change the frequency of oscillation of circuit A and this change will be transferred to the carrier developed in circuit C.

The embodiment of Fig. 2 may also be used as illustrated by Fig. 13 to transmit changes in the potential of a battery. For this purpose a resistance 61 is connected between the points designated PQ of Fig. 2, the battery 60 being connected across the resistance as shown in

Fig. 13. Changes in the battery potential will therefore be reflected as an altered grid bias of tube 34a.

Fig. 11 is an oscillogram of the signal from a frequency modulated radio transmitter of the type shown in Fig. 2; the transmitter mechanism being connected to a radio proximity fuze in a bomb, shock mounted in the bomb and dropped therewith from an altitude of 8000 feet. The amplitude of the comparison signal was approximately 3.5 volts, and the noise level was below plus or minus one volt.

It has also been found that much of the interference due to reflection from the target, as well as from the bomber, can be avoided by using lower carrier frequencies with amplitude modulation. The reduced frequency permits the use of a crystal controlled oscillator, affording excellent amplitude modulation, and when frequencies of the order of two to three megacycles per second are used no target interference is observed. A circuit diagram of a transmitter of this type is shown in Fig. 3. In this embodiment the oscillator tank coil 56 also serves as a loop antenna. The loop may be wound about the fins of the bomb, as shown in perspective in Fig. 8. Crystal 57 is connected in the grid circuit of the carrier oscillator to control the carrier frequency, as shown.

The modification of Fig. 4 may be used to transmit to a remote point measurements of the current being passed by a photo-electric cell. In this manner it is possible to check the action of a photo-electric proximity fuze while in flight. The photo-cell 54 (which may be the photo-cell which also forms a part of a fuze mechanism) is connected to the audio oscillator circuit in the manner shown. The anode of the photo-cell is connected to the positive B battery supply, and the cathode to a terminal of grid coil 52 leading to the grid of tube 53. The carrier oscillator C will be seen to be arranged as in the previous embodiments. The varying current through the photo-cell 54, under different light conditions, changes the grid bias of tube 53 since electrons are supplied to the cathode of the photo-cell by passing from the filament to the grid of tube 53 and thence through the grid coil 52 to the photo-cell. The rate of leakage of the electrons from the tube grid, which determines the bias and consequently the frequency of oscillation, will depend directly upon the rate of flow of electrons from the cathode to the anode of the photo-cell, which rate is proportional to the light flux received by the photo-cell cathode. The frequency range for a given range of photo-cell currents can be varied by adjustment of the capacitance 55 connected between the photo-cell terminal of grid coil 52 and the ground, since this capacitance is connected in series with coil 52 in the grid circuit of tube 53.

Fig. 12 shows at 70 the target pulse in a test of a photo-electric fuze dropped against a drone target, as recorded upon an oscillograph controlled by a circuit of the type illustrated in Fig. 4. The mechanism was shock mounted and frequency modulation was employed, with a nose antenna.

Figs. 5, 6 and 7 show alternative antenna constructions usable in conjunction with apparatus constructed in accordance with the present invention. In Fig. 5 the antenna tip 1, of brass or the like, is mounted in a plastic insulating rod 2 which is suitably attached to the nose of the bomb 3 from which the antenna assembly projects in coaxial position. The inductive antenna portion 4 is wound upon rod 2 and connected to the brass tip 1. Antenna coil portion 4 is connected in series with the antenna coil 5, which is inductively coupled to the tank coil 6 of the carrier oscillator. The other end of antenna coil 5 and the inner end of antenna portion 4 are grounded to the bomb casing, so that the casing and antenna function as a radiating dipole. The length of the wire in the tuning inductance 4 is approximately one quarter of the wave length of the transmitter, the antenna being of the inductance tuned type.

The antenna of Fig. 6 is of the capacitance tuned variety, the metal rod 7 being supported in an insulating bushing 8 and in series with an antenna 9 within the bomb body, the antenna coil being connected in series with the rod 7 and with the bomb body and shunted by the tuning condenser 11. It will be understood that the antenna coil is energized by the tank coil, inductively coupled thereto and fed from a circuit, of one of the forms previously described.

10 Fig. 7 illustrates an inductance tuned rocket antenna of a symmetrical form which involves the use of no protuberances which might interfere with the flight characteristics of the rocket. The nose cap portion 12 of copper or the like forms one section of the antenna dipole and is welded or otherwise fastened at its base to a copper disc 13 which is in turn attached to the insulating sleeve or ogival section 14, screwed to and forming a smooth section of the remainder of the projectile. Axially disposed within the section surrounded by the insulating ogival portion 14 is a plastic or other insulating cylinder 15, shown as held in place by a screw 16 which transfixes the copper disc. Antenna coil 17 is wound upon the form 15, one end of the coil being attached to cap 12 and the other to the bomb casing 19. Also connected to the coil 17 is the antenna coil 18, which is coupled to the tank coil of the oscillator.

Where the impulses are slow enough to permit satisfactory visual observation, a frequency meter can be used, rather than an oscillograph, to receive the signals from the transmitter.

Frequency modulated transmitters of the class herein described are also useful in making preliminary surveys of acoustic type fuzes for bombs. In this case the output of a microphone is rectified by a diode and the voltage produced is applied to the input of the transmitter. The records of the received signals then show the sound level as a function of frequency.

It will also be understood that suitable filters can be used with these telemetering transmitters to suppress any undesired frequencies, such as microphonic disturbances, and that other variations are possible without departing from the spirit and scope of the claims hereto appended.

The invention herein described may be manufactured and used by or for the Government of the United States of America for governmental purposes without the payment of any royalties thereon or therefor.

What is claimed as new and desired to be secured by Letters Patent of the United States is:

1. In combination with an explosive missile, a signalling device contained within said missile for transmitting to a remote location signals controlled by the functioning of components of the missile during flight and comprising carrier wave generating means including an electron tube arranged in an oscillating circuit, pulse generating means coupled to said wave generating means for imposing upon the carrier wave an intermittent reference signal of known amplitude, separate means coupled with said electron tube for modulating the carrier wave by signals controlled by the functioning of components of the missile during flight, said pulse generating means comprising another electron tube having cathode, grid and plate portions, feedback inductance means connected to the grid and plate portions of said last named tube and tending to cause oscillation thereof, and means comprising a frequency determining network connected to the grid portion to at least a part of said inductance means for periodically blocking said oscillation, said network being connected to said cathode portion.

2. In combination with an ordnance fuze, a telemetering transmitter comprising circuit means for developing a carrier wave; circuit means for generating an intermittent reference signal of a predetermined amplitude and including, a vacuum tube having at least cathode, plate and control grid electrodes, a D. C. supply for the cath-

ode-plate circuit of said tube, a feedback circuit including a capacitance and resistance connected between the control grid and plate electrodes of said tube for inducing oscillation of said tube, and biasing means for varying the bias voltage applied to said tube thereby to modulate the oscillatory frequency of said tube, said biasing means including a frequency changing network coupled to said control grid, a resistance coupled to said network and in the circuit with said control grid and cathode electrodes, and a voltaic cell shunted across said last recited resistance whereby voltage changes in said cell comparatively vary said bias voltage; circuit means for effecting modulation of said carrier wave by said reference signal and a signal controlled by the operation of the fuze; and antenna means for transmitting the modulated carrier wave to a remote monitoring station.
